UNITED STATES PATENT OFFICE.

HARRISON B. MEECH, OF NEW YORK, N. Y.

FURNACE.

No. 847,962.

Specification of Letters Patent.

Patented March 19, 1907.

Application filed May 10, 1906. Serial No. 316,201.

To all whom it may concern:

Be it known that I, HARRISON B. MEECH, a citizen of the United States, residing at New York, in the county of New York and State of New York, have invented a new and useful Furnace, of which the following is a specification.

This invention relates to furnaces for the production of bauxite and similar ores where intense heat is required and for which electrical furnaces are usually necessary.

The principal object of the invention is to provide a furnace in which intense heat may be attained from the use of soft coal, the coal being first coked and the gases generated being conducted through a reverberatory furnace and burned on top of the hearth, while the coke which results is forced at intervals onto a suitable grate and there burned in the ordinary manner, its combustible gases combining with those arising from fresh charges of coal in the coking-retorts and the heat from both sources being utilized after passing over the hearth for the purpose of coking the coal.

A further object of the invention is to provide a furnace which may be constructed at comparatively small expense and in which the heat is fully utilized both for coking purposes and in heating the air by which combustion is supported.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a longitudinal sectional elevation of a reverberatory furnace constructed in accordance with the invention. Fig. 2 is a transverse sectional view of the same on the line 2 2 of Fig. 1. Fig. 3 is a similar view on the line 3 3 of Fig. 1. Fig. 4 is a sectional view on the line 4 4 of Fig. 1. Fig. 5 is a plan view of the ore-drying trough in which the ore is heated and dried before being introduced into the furnace. Fig. 6 is a transverse sectional view of a portion of the underground

flue at the point where the ore-drying trough is located. Fig. 7 is a horizontal section of the escape flue or stack.

Similar numerals of reference are employed to indicate corresponding parts throughout the several figures of the drawings.

The furnace is built up of fire-brick of any suitable character and includes a combustion-chamber 10, at the lower portion of which is a suitable grate 11, and at the opposite sides of the combustion-chamber are arranged feed-doors 12, through which combustible material may be introduced when fires are started, the doors being afterward closed and luted and remaining air-tight during the operation of the furnace. Below the grate is an ash-pit 15, having suitable doors 16, through which the unconsumed cinders may be withdrawn.

The furnace-bed 17 is separated from the combustion-chamber by a bridge-wall 18, and at opposite sides and one end of the furnace-bed are suitable door-spaces 19, which may be closed by doors 20, the latter being preferably hung on counterweighted chains 8c or wire cables 21, these doors being closed and luted during the operation of the furnace. At one side is arranged a suitable tap 23, through which the material may be withdrawn.

At the top of the furnace are feed-openings 24, which are closed by slidable doors 25, formed of fire-brick or other suitable material, these being luted during the operation of the furnace. The ore is fed in when necessary by a pair of tapered hoppers 26, supported by a suitable frame 27, the hoppers gradually narrowing to small discharge-necks 28, that are arranged immediately above the openings 24, and these necks being surrounded by telescoping tubes 29, which are moved down into alignment with the openings when the covers 25 are removed.

In front of the combustion-chamber are arranged a number of retorts 30, three of which are shown in the present instance, and these retorts are tapering in width, with their narrowest ends outermost and closed by doors 31. These retorts are supplied with soft coal, which is distilled by heat from the products of combustion after leaving the furnace-bed, and the gases arising from the distilling process mingle with the products of combustion arising from the fuel on the grate and pass over the bridge-wall and into con-

tact with the ore of the furnace-bed 17. After the coking operation is completed the coke which remains is forced through the tapered retorts and thence upon the grate, 5 while fresh charges of coal are introduced into the retorts for another distilling operation.

The space below the furnace-bed is divided by two longitudinally-extending parallel walls 10 into three vertical spaces, and these are 34 again subdivided by horizontally-disposed partitions, forming a number of flues through which the products of combustion and air may pass.

15 The uppermost flues 35 at the opposite sides of the furnace communicate at one end with downtakes 36, leading from the furnace-bed, and through which the products of combustion pass after contact with the ore. The 20 heated gases pass through the downtakes and thence through the horizontal flues 35 toward the front of the furnace and at the front are directed into a central flue 37, as shown in Fig. 2, from whence they pass entirely around the coking-retorts 30, and finally escape to 25 the underground flue or stack 39, the heat imparted to the retort being sufficient to carry on the process of distillation.

The lowermost flues 40 and 41 serve for the 30 admission of air, the air from flue 41 passing upward into a flue 42 and thence upward into a horizontal flue 43, through which it travels beyond the front of the furnace, the air being heated by radiation from the products of combustion passing through the side flues 35. 35 A portion of this air passes upward through a vertical flue 44 in the bridge-wall and thence is directed through the horizontal passages 45 into the combustion-chamber at a 40 point some distance above the level of the grate. The remaining air passes through the flue 46 and upward through a vertical flue 47 and is discharged through short horizontal passages 48, leading through the front wall of the combustion-chamber. The air which 45 enters the flue 40 at one side of the furnace passes rearward and thence across and back through the other side flue 40 and is discharged from the latter flue into the ash-pit 50 at a point below the grate.

The upper central space 50 immediately below the bed of the furnace communicates with the flue 43 through a series of openings, the air heated within the space 50 passing 55 outward through a pipe 51 to be otherwise utilized in the plant.

At a suitable point between the underground flue and the main stack 52 is placed a conveyer or trough 53, in which the ore is placed and dried to an extent sufficient to 60 expel all moisture before being placed in the furnace.

In operation a fire is made on the grate with wood, coke, or other suitable combustible material, and a slow fire is continued for 65

several days to dry and season the furnace. The retorts are then filled with soft coal, and the distillation commences, the gases passing off and burning with the air over the coke fire on the grate. The fire is increased 70 to calcine the furnace-bed, after which the flux is supplied to the furnace-bed and the heat is continued until the flux becomes molten. The fine ore is then admitted from the hoppers and continued until sufficient is 75 melted to tap out into drum kettles and then manipulated as required to separate the metals from the slag.

I claim—

1. In an ore-smelting furnace, the combination with a reverberatory furnace-bed, of a combustion-chamber, a bridge-wall separating the furnace-bed from the combustion-chamber, a retort having its discharge end opening through the front wall of the combustion-chamber, and air-heating flues arranged below the furnace-bed, there being air-discharge openings in the front wall of the combustion-chamber at a point below the retort, said openings being in communication with the air-heating flues.

2. In a furnace, a reverberatory furnace-bed, a combustion-chamber, a bridge-wall separating the furnace-bed from the combustion-chamber, a retort tapering in width 95 and having its widest end opening through the front wall of the combustion-chamber, air-heating flues arranged below the furnace-bed, air-duets leading from the flues and opening through the front and rear walls of 100 the combustion-chamber, the openings in the front wall being immediately below the inner end of the retort, and escape-flues arranged adjacent to the air-heating flues and through which the products of combustion 105 pass from the furnace-bed to and around the retort.

3. In a furnace, a reverberatory furnace-bed, a combustion-chamber, a bridge-wall spacing the furnace-bed from the combustion-chamber, a retort tapering in width and having its widest end opening through the front wall of the combustion-chamber, a plurality of vertical and horizontally-disposed partitions arranged below the furnace-bed 115 and dividing the space into escape-flues for the products of combustion from the furnace-bed, and air-heating flues, a flue in communication with the escape-flue and surrounding the retort, and ducts leading from the air-heating flues and opening through the front and rear walls of the combustion-chamber.

In testimony that I claim the foregoing as my own I have hereto affixed my signature 120 in the presence of two witnesses.

HARRISON B. MEECH.
